CLAIM

The ornamental design for an egg dispenser, as shown and described.

DESCRIPTION

FIG. 1 is a first perspective view of an egg dispenser showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a sectional view thereof, taken along line 9-9 in FIG. 5; and,

FIG. 10 is an exploded view of the egg dispenser thereof. The broken lines shown in FIG. 5 indicate the cross-section of FIG. 9. All other broken lines illustrate portions of the egg dispenser. The broken lines form no part of the claim.

1 Claim, 10 Drawing Sheets
